UNITED STATES PATENT OFFICE.

FREDERIC WERDEN PANGBORN, OF JERSEY CITY, NEW JERSEY.

DESIGN FOR A PIANO-CASE.

SPECIFICATION forming part of Design No. 22,089, dated December 27, 1892.

Application filed September 24, 1892. Serial No. 446,836. Term of patent 7 years.

To all whom it may concern:

Be it known that I, FREDERIC WERDEN PANGBORN, a citizen of the United States, residing at Jersey City, in the county of Hudson and State of New Jersey, have invented and produced a new and original Design for Upright-Piano Cases; and I do hereby declare the following to be a full, clear, and exact description of the same, reference being had to the accompanying drawings, forming a part thereof.

The invention consists in the peculiar shape of a piano-case as hereinafter described and claimed.

15 The design is shown in the accompanying drawings wherein Figure 1 is a front elevation of the case and Fig. 2 is an elevation of the side D.

In the drawings the case A is shown as having the upright side B, a top C inclining down-

ward from the side B toward and terminating at the opposite side D, which latter side is recessed or curved inwardly at E near the base of the casing.

F is the key board occupying the usual position at the front.

The essential feature of the design is the inclined top of the case.

Having thus described the invention what I claim as new and desire to secure by Letters Patent is:—

The design for a piano-case, substantially as herein shown and described.

In testimony whereof I affix my signature in presence of two witnesses.

FREDERIC WERDEN PANGBORN.

Witnesses:

JOHN G. GOPSILL,

ALEXANDER MCLEAN.
